(57) **CLAIM**

The ornamental design for a foldable vehicle bed, as shown and described.

DESCRIPTION

FIG. 1 is a front perspective view of the first embodiment for a foldable vehicle bed showing our new design in a folded position;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front perspective view of the first and second embodiments for a foldable vehicle bed, showing our new design in an open position;

FIG. 10 is a rear perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a perspective view thereof;

FIG. 18 is a front perspective view of a second embodiment for a foldable vehicle bed showing our new design in a folded position;

FIG. 19 is a rear perspective view thereof;

FIG. 20 is a front elevation view thereof;

FIG. 21 is a rear elevation view thereof;

FIG. 22 is a left side elevation view thereof;

FIG. 23 is a right side elevation view thereof;

FIG. 24 is a top plan view thereof; and,

FIG. 25 is a bottom plan view thereof.

The broken lines of even length depict portions of a foldable vehicle bed that form no part of the claimed design. Additional broken lines in FIG. 17 depict environment and form no part of the claimed design.
